MATERIAL FEED DEVICE FOR GYRATORY CRUSHERS

Alexander J. Roubal, Milwaukee, Wis., assignor to Allis-Chalmers Manufacturing Company, Milwaukee, Wis., a corporation of Delaware

Application October 10, 1949, Serial No. 120,570

8 Claims. (Cl. 241—202)

1

This invention relates to material feed devices, and more specifically to those devices used in conjunction with material crushing machines such as gyratory crushers and the like. The principal object of the invention is the provision of new and improved feed devices of this type.

Heretofore in gyratory crushers, the material distributing means of the material feed devices were usually rigidly secured to the main crusher shaft. Hence every motion (including axial displacement) of the main shaft was directly imparted to the distributing means, which was undesirable.

When the clearance between crusher members was varied by vertically moving the main shaft to change the size of crushed material, clearance between the material distributing means and the material conveying means required a corresponding adjustment. This adjustment was necessary in order to maintain constant the flow of material into the crusher.

Sudden vertical displacements of the main shafts in prior art gyratory crushers, due to tramp material caught between the jaws, caused corresponding vertical displacement of the material distributing means. This of course resulted in uneven and jerky feed distribution.

It is an object of the present invention to obviate the enumerated undesirable results characteristic of prior art gyratory crushers.

Objects and advantages other than those above set forth will be apparent from the following description when read with the accompanying drawing, in which:

Fig. 1 is a vertical cross sectional view of the upper portion of a gyratory crusher embodying the invention; and

Fig. 2 is a vertical cross sectional view of another embodiment of the invention.

As shown in Fig. 1, the material crushing machine or gyratory crusher comprises a top frame 4 to which is secured the rim 5 of a spider 6. The spider 6 has arms which extend radially inward and upward from the rim 5 and terminate in a bearing housing 7 concentrically positioned above a crushing chamber 11, which chamber is defined by an inner crusher member or movable jaw 9 and an outer crusher member or stationary jaw 10. A gyratable shaft 12 is fulcrumed in a suitable bearing such as a ball and socket type bearing, 14, 15, carried in the housing 7 and retained therein by a clamp ring 16 bolted to the bearing housing and the upper end of the bearing socket. The combination of rim 5, spider 6, bearing housing 7, and bearing

2

14, 15 may be considered as a supporting structure for a material distributing means to be described hereinafter.

Adjacent to the lower end of the bearing socket 15, and held between the bearing housing 7 and a bearing portion of the gyratable shaft 12, is an oil seal 17 and a retainer 19, for preventing the escape of lubricating oil, and for preventing the entry of dust to the bearings.

The shaft 12 is gyrated at its lower end (not shown) by any suitable eccentric means and is supported to permit axial and rotary motion to be transmitted to it simultaneously with the gyratory motion. The bearing portion at the fulcrumed end of the shaft 12 is therefore rotatably and axially slidably in the bearing ball 14.

Gyratable with the crusher shaft 12 is a material distributing means, comprising a wobble plate 20 and a cylindrical member 21, one end of which concentrically supports the wobble plate.

The opposite end of the cylindrical member 21 slidably coacts with the fulcrumed end of the gyratable shaft 12 to impart an oscillating or wobble motion to the wobble plate 20. The connection between the cylindrical member 21 and the shaft 12 may be termed telescopic. The spider 6 through the bearing housing 7 axially supports the material distributing means, for example by providing a flat annular surface 24 on the bearing ball 14, for engaging in abutting relationship the edge 22 of the cylindrical member 21. Since the peripheral edge of the wobble plate 20 is subjected to considerable abrasive action from material flowing over it, a wearing ring 25 made of a relatively hard material, such as manganese steel or other suitable material, may be secured thereto to prevent excessive wear.

A resilient apron 26 of rubber or other suitable material, joins the material distributing means with the bearing housing 7. The lower end of the apron 26 is provided with a surface 27 transverse to its longitudinal axis, for engagement with a complementary surface on the bearing housing 7, and is fixed thereto by bolts 28. The opposite end of the apron 26 is formed with a surface 29 parallel to the cylindrical member 21, and may be either secured thereto by vulcanization, or in any other suitable way, or fitted snugly thereto in a slidable manner. A protective flange 30 extending radially outward from the cylindrical member 21 is secured in any suitable manner, as by a weld 31, directly above the cylinder-apron connection to protect it from damage due to material which might otherwise impinge upon it.

A primary hopper 32 is secured to the spider rim 5 and extends upwardly above the level of the wobble plate 20. The upper edge of the primary hopper 32 is provided with a flange 34 for receiving a cover plate 35 secured thereon by any suitable means. An opening 36 is formed in the cover 35 directly above the wobble plate 20 for receiving therethrough a material feed device comprising a material conveying means such as a vertically adjustable chute, designated generally by numeral 37, from which material is fed to the wobble plate 20.

The rate at which material is fed to the crushing chamber 11 is determined by the mean distance between the lower end of the adjustable chute 37 and the wobble plate 20. The greater the distance, the more material will fall on the wobble plate 20 per unit time of operation, and conversely, the shorter the distance, the less material will fall upon the wobble plate per unit of operation.

With a predetermined setting of the adjustable chute 37, and with the shaft 12 in its lowest possible position, as indicated by the upper surface 39 of the shaft, the operation of the material distributing means is as follows. As the shaft 12 gyrates, the fulcrumed end thereof, which slidably engages the cylindrical member 21, will impart a gyratory or oscillatory motion to the wobble plate 20.

In a structure wherein the apron 26 is fixedly secured to the cylindrical member 21, the apron will retain the material distributing means in a nonrotative relationship with respect to the spider 6, and at the same time will prevent upward axial displacement of the material distributing means 20 with respect to the spider 6. Hence the rotational motion of the gyratable shaft 12 about its own axis, and the axial displacements of the shaft, for example, to its uppermost position as indicated by dot dash line 40, are not transmitted to the material distributing mean 20.

The hereinbefore mentioned alternative structure, wherein the apron 26 is merely fitted snugly about the cylindrical member 21, will permit rotation of the material distributing means 20 if the rotational frictional force between the shaft 12 and the cylindrical member 21 becomes great enough to overcome the inertia of the mass of material resting on the wobble plate 20. In such a structure the clearance between the shaft 12 and the cylindrical member 21 is sufficient to allow axial displacement of the shaft without causing axial displacement of the material distributing means. Hence the material will be distributed uniformly to the crushing chamber 11 in accordance with the objects of the invention.

Fig. 2 shows another embodiment of the invention in which like elements are designated by the same reference characters as in Fig. 1 with the addition of the suffix "a." In this instance a resilient member such as an inverted apron 41, which may be substantially cylindrical or of any other suitable shape, joins the material distributing means to a bearing cap 42 carried by the bearing housing 1a. The lower end of the inverted apron 41 is provided with a transverse section 44 secured to a corresponding flat surface of the cap 42 by bolts 45. The opposite end has a similar transverse section 46 slidably held to the underside of the wobble plate 20a adjacent to its periphery by a lip portion 49 of an annular member 47 which is suitably secured to the wobble plate.

The operation of the embodiment of the in-

vention shown in Fig. 2 is similar to that of the first embodiment and need not be further described.

From the foregoing it will be apparent to those skilled in the art that the illustrated embodiments of the invention provide new and improved material distributing means for gyratory crushers and the like, and accordingly each accomplishes the objects of the invention. On the other hand, it will also be obvious to those skilled in the art that the illustrated embodiments of the invention may be variously changed and modified, or features thereof, singly or collectively, embodied in other combinations than those illustrated, without departing from the spirit of the invention, or sacrificing all of the advantages thereof, and that accordingly the disclosure herein is illustrative only, and the invention is not limited thereto.

20 It is claimed and desired to secure by Letters Patent:

1. In a material crushing machine having a stationary crusher member and a movable crusher member defining therebetween a crushing chamber, the combination of a spider carried by said stationary crusher member, a bearing universally swiveled in said spider above said crushing chamber; an axially-movable and gyratable shaft slidably journaled in said bearing, a material feed device comprising means adjustable toward and away from said chamber for conveying material toward said chamber, and material distributing means loosely journaled on said shaft in telescopically journaled relation thereto and in gyratable relation therewith, said material distributing means being in supported and substantially nonaxially movable relation to said spider and coacting with said material conveying means to provide an opening between said material conveying means and said material distributing means having a substantially constant mean dimension measured axially of said shaft, said opening providing for the substantially uniform distribution of material through said opening to said chamber during gyratory and axial movement of said shaft, said mean axial dimension of said opening being predetermined by the adjustment of said material conveying means toward and away from said distributing means.

2. In a material crushing machine having a stationary crusher member and a movable crusher member cooperatively defining a crushing chamber, the combination of a supporting structure carried by said stationary crusher member, an axially-movable and gyratable shaft slidably journaled in said supporting structure, a material feed device comprising means adjustable toward and away from said chamber for conveying material to said machine, and material distributing means carried by said supporting structure positioned above said chamber and below said material conveying means in substantially nonaxially movable relation to said structure, said distributing means being loosely journaled on and gyratable in response to gyratory movement of said shaft, said material distributing means coacting with said material conveying means to provide an opening therebetween having a substantially constant mean dimension measured axially of said shaft, said opening providing for the substantially uniform distribution of material to said chamber during gyratory and axial movement of said shaft, said mean axial dimension of said opening being predetermined by the adjustment of said material

conveying means toward and away from said material distributing means.

3. In a material crushing machine having a stationary crusher member and a movable crusher member cooperatively defining a crushing chamber, the combination of a spider carried by said stationary crusher member; a bearing universally swiveled in said spider above said crushing chamber; an axially-movable and gyratable shaft slidably journaled in said bearing; a material feed device comprising means adjustable toward and away from said chamber for conveying material to said machine; and material distributing means loosely journaled on said shaft and axially supported in substantially nonaxially movable relation to said spider by said bearing below said material conveying means for gyration with said shaft, said material distributing means coacting with said material conveying means to provide an opening therebetween having a substantially constant mean dimension measured axially of said shaft, said opening providing for the uniform distribution of material to said chamber during gyratory and axial movement of said shaft relative to said spider, said mean axial dimension of said opening being predetermined by the adjustment of said material conveying means toward and away from said distributing means.

4. In a material crushing machine having an inner crusher member and an outer crusher member cooperatively defining a crushing chamber; the combination of a spider carried by said outer crusher member; a bearing universally swiveled in said spider above said crushing chamber; an axially-movable and gyratable shaft slidably journaled in said bearing; a material feed device comprising means adjustable toward and away from said chamber for conveying material to said machine; and material distributing means disposed beneath said material conveying means for gyration with said shaft, said material distributing means comprising a sleeve portion loosely journaled on said shaft and axially supported in substantially nonaxially movable relation to said spider by said bearing, and a plate portion connected to said sleeve portion for receiving material from said material conveying means for distribution to said chamber, said plate portion coacting with said material conveying means to provide an opening therebetween having a substantially constant mean dimension measured axially of said shaft, said opening providing for the uniform distribution of material to said chamber during gyratory and axial movement of said shaft, said mean dimension being predetermined by the adjustment of said material conveying means toward and away from said distributing means.

5. In a material crushing machine having a stationary crusher member and a movable crusher member cooperatively defining a crushing chamber, the combination of a spider carried by said stationary crusher member; a bearing universally swiveled in said spider above said crushing chamber; an axially-movable and gyratable shaft slidably journaled in said bearing; a material feed device comprising means adjustable toward and away from said chamber for conveying material to said machine; material distributing means loosely journaled on said shaft and axially supported in substantially nonaxially movable relation to said spider by said bearing below said material conveying means for gyration with said shaft, said material distributing means coacting

with said material conveying means to provide an opening therebetween having a substantially constant mean dimension measured axially of said shaft, said opening providing for the uniform distribution of material to said chamber during gyratory and axial movement of said shaft relative to said spider, said mean axial dimension of said opening being predetermined by the adjustment of said material conveying means toward and away from said distributing means; and sealing means interposed between said spider and said material distributing means for shielding and protecting said bearing.

6. In a material crushing machine having an inner crusher member and an outer crusher member cooperatively defining a crushing chamber, the combination of a spider carried by said outer crusher member; a bearing universally swiveled in said spider above said crushing chamber; an axially-movable and gyratable shaft slidably journaled in said bearing; a material feed device comprising means adjustable toward and away from said chamber for conveying material to said machine; and material distributing means disposed beneath said material conveying means for gyration with said shaft, said material distributing means comprising a sleeve portion loosely journaled on said shaft and axially supported in substantially nonaxially movable relation to said spider by said bearing and a plate portion connected to said sleeve portion for receiving material from said material conveying means for distribution to said chamber, said plate portion coacting with said material conveying means to provide an opening therebetween having a substantially constant mean dimension measured axially of said shaft, said opening providing for the uniform distribution of material to said chamber during gyratory and axial movement of said shaft relative to said spider, said mean dimension being predetermined by the adjustment of said material conveying means toward and away from said distributing means; and an annular resilient apron interconnecting said spider and said sleeve for sealing and protecting said bearing against the entrance of foreign material thereinto.

7. In a material crushing machine having a stationary crusher member and a movable crusher member cooperatively defining a crushing chamber, the combination of a spider carried by said stationary crusher member, a bearing universally swiveled in said spider above said crushing chamber, an axially-movable and gyratable shaft slidably journaled in said bearing, a material feed device comprising means adjustable toward and away from said chamber for conveying material toward said chamber, material distributing means associated with said shaft in axially slidable relation thereto and in gyratable relation therewith, said material distributing means being in supported and substantially nonaxially movable relation to said spider and coacting with said material conveying means to provide an opening therebetween having a substantially constant mean dimension measured axially of said shaft, said opening providing for the substantially uniform distribution of material through said opening to said chamber during gyratory and axial movement of said shaft, said mean axial dimension of said opening being predetermined by the adjustment of said material conveying means toward and away from said distributing means, and resilient means interconnecting said spider and said material dis-

tributing means for sealing and protecting said bearing to prevent the entrance of foreign material therein, said resilient means cooperating with said spider in maintaining said material distributing means in supported relation thereto.

8. In a material crushing machine having a stationary crusher member and a movable crusher member cooperatively defining a crushing chamber, the combination of a supporting structure carried by said stationary crusher member, an axially-movable and gyratable shaft slidably journaled in said supporting structure, a material feed device comprising means adjustable toward and away from said chamber for conveying material to said machine, material distributing means carried by said supporting structure in substantially nonaxially movable relation to said structure positioned above said chamber and below said material conveying means and gyratable in response to gyratory movement of said shaft, said material distributing means coacting with said material conveying means to provide an opening therebetween having a substantially constant mean dimension measured axially of said shaft for the uniform distribution of mate- 25

rial to said chamber during gyratory and axial movement of said shaft, said mean axial dimension of said opening being predetermined by the adjustment of said material conveying means toward and away from said material distributing means, and sealing means interposed between said supporting means and said material distributing means for shielding and protecting said bearing.
